UNITED STATES PATENT OFFICE.

HENRY H. EVERETSEN, OF MERIDEN, CONNECTICUT, ASSIGNOR TO WILCOX
& EVERETSEN, OF SAME PLACE.

DESIGN FOR A HANDLE FOR SPOONS, FORKS, &c.

SPECIFICATION forming part of Design No. 30,716, dated May 9, 1899.

Application filed March 1, 1899. Serial No. 707,414. Term of patent 3½ years.

To all whom it may concern:

Be it known that I, HENRY H. EVERETSEN, of Meriden, in the county of New Haven and State of Connecticut, have invented and produced a new Design for a Handle for Spoons, Forks, and Similar Articles; and I do hereby declare the following, when taken in connection with the accompanying drawings and the letters of reference marked thereon, to be a full, clear, and exact description of the same, and which said drawings constitute part of this specification, and represent, in—

Figure 1, a face view of a spoon or fork handle embodying my design; Fig. 2, a reverse view thereof.

This invention relates to a design for a handle for spoons, forks, and similar articles; and it consists in the configuration and ornamentation as shown in the accompanying illustrations and hereinafter described.

As herein shown, the design consists of a rich border of scrolls A and conventionalized floral forms B, applied to the end of a handle C, which is of the so-called "fiddle-pattern"

in general outline or form, the stem C' of the handle being perceptibly enlarged midway of its length and thence tapering gracefully outward and inward. The face of the handle is somewhat more elaborately ornamented than the reverse thereof, the face of the handle being enriched by a floral ornament D at the juncture of the end of the handle and the stem. At the juncture of the stem and the bowl or fork the handle is richly ornamented with scrolls E, which on the reverse side of the stem are extended onto the bowl or fork, as at F.

I claim—

The design for a handle for spoons, forks and similar articles as herein shown and described.

In testimony whereof I have signed this specification in the presence of two subscribing witnesses.

H. H. EVERETSEN.
